United States Patent Office

Des. 221,642
Patented Aug. 31, 1971

221,642

PEW

Theodore L. Bayes, Tacoma, Wash.
(1705 Belmont Ave., Seattle, Wash. 98122)

Filed Dec. 24, 1969, Ser. No. 19,993

Term of patent 14 years

Int. Cl. D6—01

U.S. Cl. D15—11

FIG. 1 is a rear perspective view from its aisle end of my new design of a pew;

FIG. 2 is a front perspective view, from its aisle end of the pew;

The end of the pew, not shown, is conventional in configuration. The bottoms of the seat cushion supports are regular plane surfaces.

I claim:

The ornamental design of a pew, as shown and described.
